(57) **CLAIM**

We claim the ornamental design for a projecting display mount, as shown and described.

DESCRIPTION

FIG. 1 is a first perspective view of a projecting display mount showing our new design, wherein the break lines indicate indeterminate length;

FIG. 2 is a second perspective view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear elevational view thereof.

The broken line showing of mounting holes and bolts is included for the purpose of illustrating environment and forms no part of the claimed design.
